UNITED STATES PATENT OFFICE.

CHARLES WILD, OF EUREKA, CALIFORNIA.

WELL DRILL.

Application filed October 16, 1924. Serial No. 743,989.

This invention relates to well drilling tools and aims to provide a drill of a novel construction including tubing and movable cutting jaws arranged adjacent to the lower 5 end of the tubing, the jaws being constructed so that they may be moved to positions beyond the lower end of the tubing to cut a path for the tubing.

Another important object of the invention 10 is to provide a drill of this character which will accomplish the drilling result and at the same time preserve a core for testing purposes, which core is removed by a specially designed tool.

15 A still further object of the invention is the provision of movable cutting jaws that are automatically moved from their inactive to their active positions at the limit of the downstroke of the drill.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawings:

Figure 1 is an elevational view illustrating the lower end of a drill constructed in accordance with the invention, the cutting jaws being shown in their active positions.

30 Figure 2 is a longitudinal sectional view through the drill.

Figure 3 is a bottom plan view thereof.

Figure 4 is a sectional view taken on line 4—4 of Figure 2.

40 Figure 5 is a sectional view taken on line 5—5 of Figure 2.

Figure 6 is a sectional view taken on line 6—6 of Figure 2.

45 Figure 7 is a perspective view of one of the connecting links.

Figure 8 is a perspective view of one of the cutting jaws.

50 Referring to the drawings in detail, the reference character 5 indicates the outer casing of the drill in which the drill casing 6 moves. The reference character 7 indicates the head of the drill casing which is secured within the casing by means of the bolts 8, the head 7 being provided with an 55 opening through which the controlling rod 9 moves. Disposed within the drill casing

6 and arranged in spaced relation with the head 7 is a circular partitioning member 10 formed with a bearing 11 through which the rod 9 moves and is guided, during the 60 operation of the drill.

Arranged at the lower end of the drill casing 6 and disposed in spaced relation with each other are blocks 12 which are secured to the casing 6 by means of rivets 13 and as shown, each of these blocks 12 is formed with an ear 14 apertured to receive the shafts 15 that secure the connecting link 16 to the blocks 12 in a manner to permit the link 16 to swing vertically.

70 The shanks 18 are formed with openings 18' that receive shafts 19' for securing the jaws 19 to the links 16. At the lower end of the drill casing 6 is guide member 17 formed with openings through which the shanks 18 of the cutting jaws 19 move, the openings being arranged at oblique angles so that when the jaws are moved to their active positions, the lower ends thereof will extend beyond the outer surface of the casing 5 to undercut the lower end of the casing 5 and allow the casing to move downwardly.

75 As illustrated by Figure 2 of the drawings, the rod 9 is formed with a threaded extremity 20 on which the members 21 and 22 are positioned, the members 21 and 22 being held in spaced relation with each other to accommodate the heads 23 of the links 16, to the end that reciprocating movement of the rod 20 will result in movement of the connecting links 16 to move the cutting jaws 80 into and out of their active positions.

85 A coiled spring indicated at 24 has its lower end engaging the member 21 that acts as a seat for the coiled spring, while the opposite end of the coiled spring 24 engages under the partitioning member 10. This spring 24 normally acts to urge the members 21 and 22 downwardly towards the 90 lower end of the casing 5 when the drill proper has been released or dropped into the well being drilled.

100 Formed at the upper end of the rod 9 is an eye 25 to which a suitable hook may be connected, the hook being of the usual type employed in the drilling of wells to permit of a quick and easy application of the hook. The device is supported by the usual twisted cable which gives the device a slight rotary movement as it is dropped to the end that 105 the jaws will be shifted and will not be 110

dropped into the same position with each movement of the rod 9.

In the operation of the device, it will be obvious that when the rod 9 is lifted, the 5 jaws are automatically moved to positions within the confines of the casing 6 and that when the rod is released or dropped to accomplish the digging result, the spring 24 acts to urge the jaws outwardly to positions 10 to undercut the casing 5 and allow the casing 5 to feed downwardly into the opening formed. Continuous reciprocation of the jaws results in the cutting or underreaming 15 of the wall to allow the casing 5 to move downwardly.

It will be obvious that the device cuts into the ground with each downward movement of the rod 9, leaving a central core which is removed by an especially constructed tool 20 forming the subject matter of a separate application, the finer particles of stone and earth being removed by the well known bailer system.

I claim:—

- 25 1. A drilling tool including a drill casing, blocks secured within the drill casing and arranged in spaced relation with each other, connecting links having pivotal connection with the blocks and having heads, jaws having connection with the links at points intermediate the ends of the links, means operating through the drill casing and engaging the heads of the links to move the jaws so that the cutting surfaces thereof will extend 30 beyond the end of the drill casing.
- 35 2. A drilling tool including a drill casing, a rod extending through the casing and having adjustable members arranged on the lower end thereof, links having pivotal con-

nection with the inner surface of the drill 40 casing and having their free ends disposed between the adjustable members to connect the links to the rod, cutting members having pivotal connection with the links and adapted to move at oblique angles with respect to the drill casing to cause the cutting members 45 to be extended beyond the lower end of the drill casing to cut the ground surface below the drill casing.

3. A drilling tool including a drill casing, 50 a partitioning member within the drill casing, a rod extending through the partitioning member, connecting members mounted on the rod, cutting members extending into the drill casing, means having connection with the upper ends of the cutting members 55 and positioned between the connecting members for moving the cutting members when the rod is moved, and a coiled spring engaging the partitioning member and resting on one of the connecting members for normally urging the cutting members to their active positions.

4. A drilling tool including a drill casing, 60 an inner movable drill casing, a vertically movable rod within the inner casing, a head on the rod, jaws within the inner casing, means connected with the inner casing and engaging within the head for connecting the jaws and rod, a guiding member through 65 which the jaws move, said guiding member being carried by the inner casing, and a coiled spring on the rod for normally urging the rod downwardly.

In testimony that I claim the foregoing as 70 my own, I have hereto affixed my signature.

CHARLES WILD.
